UNITED STATES PATENT OFFICE.

ALBERT H. TINNERMAN, OF CLEVELAND, OHIO.

MANIFOLD FOR GAS RANGES.

Application filed April 20, 1927. Serial No. 185,108.

This invention relates to stove construction and more particularly to means for covering the manifold and valve parts of a gas range. The usual construction of gas ranges includes a gas manifold, shut-off valves and air mixers which are placed in front of the range. Thus, the manifold valves and mixers are exposed to view and are subjected not only to dust, which readily accumulates on the mixer, but are also subjected to discoloration by any material which may be spilled upon the stove.

An object of the present invention therefore is to provide means for protecting the valve and mixer mechanism not only from the accumulation of dirt, but also from material which may flow onto the stove top and over the edge thereof. In this connection my invention contemplates a protecting device, which may be readily attached to a stove, and which when so attached permits adjustments of the valves and mixers to be made in an expeditious manner.

Referring to the drawings, Fig. 1 is a perspective view of a stove embodying my invention; Fig. 2 is a vertical section through the stove on a plane indicated by the line 2-2 in Fig. 1; while Fig. 3 is a perspective view of a manifold cover, while in inverted position.

I have illustrated my invention in connection with a stove having a frame 10, on which a stove top, indicated at 11, is supported in the usual way. A gas manifold 12 extends along the front edge of the stove top and has spaced conduits 13 leading therefrom to the respective burners, each conduit has a gas valve 14 connected thereto near the manifold, and has an air mixing valve 15 indicated in Fig. 2. Each valve, as illustrated, has a valve stem 16 projecting upwardly therefrom and has an operating handle 17 mounted on the outer end of the stem.

The present invention is in the nature of a hood or cover 20 which is preferably slightly longer than the length of the manifold and which is arranged to be attached to the stove top in such manner that it may be rigidly held in position. One form of means for holding the cover in place is illustrated as comprising a pair of brackets 21, which are attached at one end to the stove top by securing members 22. These brackets project outwardly and downwardly from the stove top and are suitably curved at the outer ends to receive the manifold. These

brackets form supports upon which the cover rests. The cover has spaced pads 23 which are shaped to engage recessed portions in the brackets, and are adapted to be attached thereto as by securing members 24. Each pad is preferably curved near the outer end to engage the manifold. Thus, the manifold is securely clamped in position by the securing members, which function to hold the cover in place.

The cover has spaced openings 25 through which the valve stems extend. Thus, the only parts exposed to view are the operating handles and the associated valve stems. In this way adequate protection is afforded to the fuel and air valves, while at the same time sufficient room is provided for enabling adjustment of the valves to be made.

Having thus described my invention, I claim:

1. In combination, a stove top, a gas manifold disposed beneath and in front of the top, a plurality of conduits leading from the manifold, a valve associated with each conduit and projecting therefrom, and a hood extending downwardly and outwardly from the stove top, and also downwardly over the outer side of the manifold, said hood having spaced openings in the top thereof through which said valve stems extend.

2. In combination, a stove top, a gas manifold mounted in front of and beneath the top, a plurality of valves associated with the manifold, a hood covering the manifold and valves, and an operating member associated with each valve and disposed outside and above the hood.

3. In combination, a stove top, a gas manifold mounted in front of and beneath said top, a plurality of gas valves associated with the manifold and each having a stem projecting upwardly therefrom, an operating handle associated with each stem, a hood associated with said top, said hood extending across the manifold and valves, and the bottom edge of the hood terminating on a line near the bottom of the manifold, said hood having openings therein through which said valve stems extend, and said handles being disposed on the upper side of said hood.

4. In combination, a stove top, a gas manifold mounted in front of and beneath said top, a plurality of valves associated with the manifold, a hood extending outwardly

from the top and downwardly over the manifold and terminating beneath the bottom of the manifold, said hood having openings therein, and said valves having stems 5 projecting through said openings, a handle associated with each stem and operable from a point above the hood, and said cover having at least one end thereof closed.

5. In combination, a stove top, a gas manifold mounted in front of and beneath the said top, a plurality of valves associated with the manifold, a stem and handle associated with each valve, a hood extending

outwardly from the top and downwardly over the outer side of the manifold, said 15 hood having openings through which the respective stems extend, whereby the handles may be operated from points above the hood, each end of said hood having a downturned flange enclosing the ends of the manifold, 20 the bottom of said flanges and the horizontal end of the hood lying substantially in the same plane.

In testimony whereof, I hereunto affix my signature.

ALBERT H. TINNERMAN.
